United States Patent Office

Des. 184,168
Patented Dec. 30, 1958

184,168

MAIL BOX OR THE LIKE

George W. Cornell, Miami, Fla., assignor of one-half to
W. Elder Cornell, Jr., Miami, Fla.

Application November 14, 1957, Serial No. 48,449

Term of patent 14 years

(Cl. D74—9)

Fig. 1

I claim:

The ornamental design for a mail box or the like, as shown and described.
